UNITED STATES PATENT OFFICE.

HOWARD T. HALLOWELL, OF JENKINTOWN, PENNSYLVANIA.

FEET FOR DISPLAY SIGNS.

Application filed September 12, 1923. Serial No. 587,720.

One object of this invention is to provide a novel form of foot for supporting frames such as those commonly employed for advertising or display purposes, the invention 5 contemplating a simple, rugged and relatively inexpensive construction of substantial and ornamental appearance.

It is further desired to provide a novel method for forming a sign foot from suitable sheet material with the expenditure of a minimum of said material.

These objects and other advantageous ends I attain as hereinafter set forth, reference being had to the accompanying drawings, 15 in which:

Fig. 1 is a perspective view of a sign frame, showing my improved foot structures applied thereto;

Fig. 2 is a detached perspective view of 20 one of the feet;

Fig. 3 is a plan view of a sheet metal blank from which the foot may be made;

Fig. 4 is a perspective view, showing a 25 partially formed foot made from the blank illustrated in Fig. 3;

Fig. 5 is a perspective view of a slightly modified form of foot;

Fig. 6 is a perspective view of another 30 modified form of the foot;

Fig. 7 is a plan view of the sheet metal blank from which the foot illustrated in Fig. 6 is made; and

Fig. 8 is a vertical sectional view of a 35 still further modification of the invention.

In carrying out my invention I employ sheet steel of suitable thickness and in order 40 to construct one form of my sign foot by means of suitable dies, I first form a flat blank such as is shown in Fig. 3. This includes a substantially rectangular body portion 1 from which project three elongated and substantially rectangular tongues 2—2 and 3, of which the latter lies between and 45 parallel with the other two, but from which it is separated by slots 4—4; its length being preferably slightly more than half that of the tongues 2.

A series of holes 5—5 may be formed in the body 1 and in the middle tongue 3, either 50 when the blank is formed or subsequently, after which said blank is subjected to the action of a press, whereby the two tongues are given a similar curved outline so that they project to one side of the plane of the body 1 and tongue 3, while their extremities

6 are bent so that they lie in a plane at right angles to said plane of the body.

This partially formed structure, shown in Fig. 4, is now subjected to another pressing or forming operation whereby the longitudinal sides of the body 1 are turned at right angles so as to lie parallel with each other, as indicated at 7 in Fig. 2, and the legs formed by the curved tongues 2 are thus each swung through 90° so that they curve 60 in opposite directions away from the base of the channel-shaped body portion. At the same time the tongue 3 is likewise bent at right angles to the main portion of the body to constitute the bottom thereof as shown in 65 Fig. 2; it being noted that by reason of the slots 4—4 its edges are spaced away from the adjacent portions of the parts 2.

If, as in Figs. 1 to 4 inclusive, the portions 6 are integral with the side members 2, they constitute the ground-engaging portions of the foot, and said side members are preferably tied together and braced by a transverse element in the form of a bar 8 whose ends are riveted to said members. If 70 desired, I may omit the portions 6 from the blank, merely giving the tongues 2 an arcuate form, and providing a base member 8a in the form of a relatively heavy elongated bar having at its ends portions 6a offset adjacent said portions to fit between the curved legs 2a of the pressed up structure. These, 75 as before, are connected to the base member by rivets 10 see Fig. 5.

The central tongue of each foot serves as 80 a bottom for the channel-shaped body portion of the finished foot and extends under the bottom of the rectangular sign frame α , as shown clearly in Fig. 1. The channel-shaped body of each foot section is so shaped as to 85 fit closely the side members of the frame α . Screws, or bolts, extend through the holes 5 of the body portion and the bottom extension 3 and into the frame α . This construction not only rigidly supports the frame 90 on the feet, but also strengthens the corner joints of the frame, making a substantial structure. The legs are preferably formed of pressed up ribs 12 or 12a, which stiffen the legs, particularly at the point of junction 95 with the body portion.

In that form of the invention shown in Fig. 5, the base member 8a is preferably made of abnormal weight so as to add stability to the combined structure formed by 100 110

the sign frame and its two feet and the latter are connected to the sign frame by bolts or screws passed through the holes 5.

Without departing from my invention, I 5 may make the foot as shown in Fig. 6 with curved legs 2 and a substantially cylindrical body portion 13 formed by rolling up a substantially rectangular piece of sheet metal, Fig. 7, to which both legs are attached. 10 This body is integrally connected to the legs at one side and is preferably open to provide a longitudinally extending slot 14 at the opposite side for receiving a vertical sign or frame structure to which it is attached. 15

From the above description it will be appreciated that the foot made in accordance with my invention is not only relatively strong and rugged, but may be economically 20 made with a minimum of labor and material; it being noted that by providing the slots 4 there are in the finished brackets openings between the sides or flanges 7 and the bottom tongue 3 which permit of the free 25 running out of any water running down the sides of a sign supported by a pair of said brackets.

Under certain conditions and without departing from my invention, the tongue 3 30 may be omitted and as shown in Fig. 8, replaced by an angle piece 20. One branch of this latter extends parallel and in engagement with the face of the body 1, while the other branch projects horizontally in position to engage and support the bottom edge 35 of a sign frame or equivalent structure.

I claim:—

1. As a new article of manufacture, a 40 struck up sheet metal foot for a sign, consisting of a body portion having a flange

at each side; a leg forming a continuation of each flange and extending below the body portion; a tongue forming a continuation of the body portion and bent at right angles and extending between the legs and forming a bottom support for a sign to which the foot is attached. 45

2. The combination of a sign; two feet supporting the said sign, each foot being 50 at a lower corner of the sign, the said feet being made of struck up sheet metal and having a body portion flanged to form supports for the sign; two legs on each foot portion extending at right angles to the body of the sign, each foot portion having 55 an integral tongue bent at right angles to the body portion and extending between the legs and forming the bottom support for the sign to which it is secured; and a brace extending from one leg to the other below the tongue. 60

3. The combination of a rectangular sign; a foot located at each lower corner of the sign and forming a corner brace for the sign, each foot being made of struck up 65 sheet metal and consisting of a body portion having a flange at each side forming a channel for the sign; two legs integral with the body portion and forming a continuation of the flanges; a tongue forming 70 a continuation of the body portion and bent at right angles to said body portion, said tongue extending between the legs and projecting at one side thereof and forming a brace support for the sign; a brace extending from one leg to the other below the tongue; and means for attaching the body 75 portion and tongues of the feet to the sign.

HOWARD T. HALLOWELL.
